UNITED STATES PATENT OFFICE.

JAMES A. BRENT, OF SAN FRANCISCO, CALIFORNIA.

ORE-CONCENTRATOR.

1,295,960.

Specification of Letters Patent.

Patented Mar. 4, 1919.

Application filed March 1, 1916; Serial No. 81,428. Renewed July 22, 1918. Serial No. 246,231.

To all whom it may concern:

Be it known that I, JAMES A. BRENT, a citizen of the United States, residing at San Francisco, in the county of San Francisco and State of California, have invented certain new and useful Improvements in Ore-Concentrators, of which the following is a specification.

My invention relates to an improvement in ore concentrators, and the object is to provide a simple means of adjustment of the riffles to adapt them to varying conditions of work and material being treated; and it consists in the main in a flexible adjustable riffle, the transverse inclination and longitudinal twist of which may be adjusted and varied to suit the requirements.

In the accompanying drawings:—

Figure 1 is a view in perspective of the frame showing several of my improved tables suspended therein;

Fig. 2 is a plan view of one of the details;

Figs. 3 and 4 are enlarged side elevations showing the adjustable side of the riffle, Fig. 3 with the riffle adjusted to its lower position, and Fig. 4 showing it partly down and partly raised;

Fig. 5 is an enlarged view taken from the lower end of the machine;

Figs. 6 and 7 are cross-sectional details on a still larger scale; and

Fig. 8 is a perspective showing the lower ends of the riffles.

A represents a frame or superstructure; B, is the head-motion; C is a beam or bolster suspended in any approved manner; and to this are connected the tables 1, 2, 3 and 4, or as many as the frame is constructed to accommodate, any approved means of connection with the bolster and suspension from the frame being adopted. As this frame is no part of the present invention, it will be unnecessary to go further into details.

As one table is a type of all, it will be necessary to describe one only.

While the general shape might be varied indefinitely, an approved form is that illustrated in Fig. 2, in which the table gradually widens toward the concentrates discharge end at the right, the head-motion end at the left being the smaller. Three sides are surrounded by the upstanding edges 5, 5, whereas the remaining right-hand edge 55 is open for the escape of both the concentrates and the gangue at their different

areas. The head-motion 6 is attached at the smaller or left-hand end, as illustrated in Figs. 1 and 2.

The riffles, which constitute the essential part of my improved concentrator, occupy an area preferably extending throughout the length of the table, (as shown in Fig. 2) commencing a few inches from the upper or feed side, which is the uppermost side, (as illustrated in Fig. 2) the table being of the type which is tilted sidewise and reciprocated lengthwise in order to give the metallics a progressive endwise feed lengthwise of the riffles, and to allow a side-wash of the water used in the process of concentration.

The riffles comprise in the main two parts, namely the matched or tongue-grooved strips 7 (as shown better in Figs. 5, 6, and 7). After fitting these together, they are secured by means of the bolts 8 which extend therethrough, and which are placed at intervals of about twelve inches apart throughout the length of the table, (as indicated by dotted lines in Fig. 2, and as shown in section in Figs. 3 and 4).

These strips 7 are supported on transversely arranged channel-irons 9, to which the strips are secured by bolts 10, (as shown in Fig. 8). Over the top of each strip 7, the flexible, adjustable riffles R are secured. These are preferably made of sheet-copper, and consist of the land or central portion 11 and the two flanges 12 and 13. The width of each riffle approximately corresponds with the width of its corresponding strip 7, to which it is secured, and adjustably connected at one edge, (as shown very clearly in Figs. 5 and 6). The flange 12 at the right is secured rigidly to one edge of the strip 7, to which it is attached by a screw nail, or equivalent means 14, and the opposite flange 13 is provided with slots 15, which receive and straddle the bolts 8 (as shown in Figs. 3 and 4), the object of which is readily understood, namely to admit of the riffle being adjusted to merely change the inclination of angle of the land (as shown in Figs. 3, 5, 6 and 7), or to give it not only a change of angle but also permit of a twisting adjustment, (as shown in Fig. 4), that is to say to adjust it so that the elevation of its adjustable side or edge may vary throughout the length of the riffle, which is sometimes quite desirable.

It is understood, of course, that one edge,

TOMMY T. KELLEY, PETROLEUM CONCENTRATOR

namely the edge having the flange 12 is rigid, in other words, the adjustment is from the upper edge of this flange through the medium of the riffle, the spring of the sheet 5 copper forming the riffle admitting of this adjustment.

The adjustment is done by means of a gage (not shown) which is extended along the edges of the riffles at a time either in 10 the construction or re-adjustment of the table when the nuts 16 on the bolts 8 are loosened, and after these riffles are all adjusted with the strips 7, 7, held by the bolts 8 and the nuts 16 sufficiently tight to create 15 a frictional contact to hold the riffles where set, then the nuts are screwed up on the bolts, drawing the strips and riffles into tight and rigid contact with one another, thus holding the riffles and their strips rigidly in 20 place as a solid body, until action may occasion loosening them up and re-adjusting.

In this way, it is also possible to easily apply a new riffle or riffles at any time, should one become worn or defective or require a change of angle or twist to suit a 25 special condition of concentration.

Along the lower edge of each riffle, a groove 17 is formed, the purpose of which is to catch the very fine metallics, holding 30 them in a sheltered position beneath the overhang or ledge 18 formed in the riffle above, (as clearly illustrated in Fig. 6). At this position, the very fine particles which require protection are sheltered almost 35 entirely from side-wash of water flowing transversely over the riffles, there being just enough splash and backflow to clean off the gangue, and yet leave the metallics undisturbed, so that they settle quickly and travel 40 down to the concentrates discharge end at the right.

The riffles terminate at the concentrates discharge end of the table in wings 19, which project a trifle beyond the end of the table, 45 and thus protect the metallics discharging from the ends of the riffles from the side-wash down the slope of the table. A space or channel 20 is formed throughout the length of the upper edge of the 50 table, in which the richer metallics are caught, and from which they are conveyed to the concentrates discharge end of the table.

A relatively smooth space 21 is formed at 55 the opposite edge of the table, over which the gangue is caused to discharge in a trough-like dip formed by the sheet-metal 60 covering 22 of the table at this point (as shown in Fig. 5). At the feed end of this portion 21, holders or settlers 23 are arranged diagonally, they being adapted to 65 retard the flow of gangue and hold the material in suspension by reason of the ponding 70 or pool thus formed. The semi-soft material under treatment is fed upon the table at 75 125

The table is tilted to the desired inclination, as is well understood, by suitable adjustments on the frame A of the machine. The table is reciprocated at any desired speed. The side-wash of water clears the 70 metallics of the gangue by floating the gangue off while the metallics settle almost instantly either in the channel 20, or on the first two or three riffles, where, by reason of the adjustment of these riffles, it is held 75 during its travel throughout the length of the table.

A very large percentage of the total separation therefore takes place at the feed end, and almost instantly upon the material 80 reaching the surface of the table. Therefore, long before the discharge end of the table shall have been reached, the gangue has been thoroughly separated from the metallics, and so far as actual separation is 85 concerned, the major part has been completed long before the material has traveled half the length of the table, but, nevertheless, to insure the greatest efficiency and capacity of the table, the whole length 90 provided is desirable as is readily understood.

I claim:

1. In a concentrator, a transversely bendable sheet-metal riffle extending lengthwise thereof comprising a land having a flange at 95 each edge, the land having a groove formed longitudinally approximately at the juncture with one flange and an overhang formed approximately at the juncture of the opposite edge of the land with the other 100 flange and means for variably bending the riffle longitudinally of the table.

2. In a concentrator, a transversely bendable sheet metal riffle extending lengthwise thereof comprising a central land with a 105 flange throughout its length at each edge, one flange having means whereby it is rigidly secured to the table and the other flange having means whereby it may be 110 variably vertically adjusted with relation to and longitudinally of the table.

3. In a concentrator, the combination with a strip, of a flexible riffle comprising a land and flanges at each edge thereof, and means 115 for securing one flange fixedly to one edge of the strip and the other flange adjustably to the other edge of the strip at different elevations throughout its length, whereby the transverse elevation of the land may be 120 varied throughout its length.

4. In a concentrator, the combination with a plurality of parallel strips, of flexible 125 sheet metal riffles extending lengthwise thereof, each comprising a land and two flanges, one flange of each strip being permanently secured to one side of a strip, and the other flange adjustably secured to the opposite edge of the strip, at elevations varying longitudinally of the 130 strip, and means for drawing the strips to

- gether to frictionally hold the adjustable flanges in place where set.
5. In a concentrator, the combination with strips, running lengthwise thereof of longitudinal riffles made of sheet-metal each comprising a land and two flanges, one of which is permanently secured to one edge of each strip, and the other variably adjustably connected with the opposite edge of each strip 10 whereby to vary the inclination of the riffle along its length.
6. In a concentrator, the combination with strips, of riffles made of sheet-metal each comprising a land and two flanges, one of 15 which is permanently secured to one edge of a strip, the other adjustably connected at varying elevations with the opposite edge of each strip, and common means for securing said strips and flanges rigidly in 20 place.
7. In a concentrator, the combination with cross-beams and strips secured thereon of sheet-metal riffles each having one edge fixed and the other edge adjustably connected with the strips at varying elevations. 25
8. In a concentrator, the combination with cross-beams and strips secured thereon, of sheet-metal riffles adjustably connected with the strips, and common means for holding 30 said riffles in their adjusted position.
9. A concentrator table having a plurality of riffles extending throughout the length of a central belt of the table, with relatively smooth spaces on either side, one of which forms a channel for the metallics, and the other a discharge for the gangue, and settlers placed diagonally across the feed end of one of said smooth spaces. 35
10. In a concentrator, the combination with a table, of flexible hollow riffles thereon, the ends of which terminate in vertically-disposed wings which extend beyond the end of the table. 40
11. In a longitudinally reciprocating concentrator table which gradually widens from the feed to the discharge end, and which has three edges raised above the working surface of the table, a set of riffles extending in the direction of the stroke and so disposed on the surface of the table that a relatively 45 smooth surface is located on each side thereof, so that both concentrates and gangue discharge at the same end of the table, one of said smooth surfaces gradually increasing in area toward the discharge 50 end for the escape of the gangue, and settlers disposed diagonally across the feed end of the lower smooth surface. 55

In testimony whereof I affix my signature.
JAMES A. BRENT.
